pany, Syracuse, N. Y., a corporation of Massa-
chusetts

Application September 29, 1930
Serial No. 483,207

11 Claims. (Cl. 198—21)

This invention relates to conveyor systems of the general type comprising main and branch conveyors or similar arrangements, providing junction points where material may be delivered from one conveyor to the other. In such systems it is possible for the articles (carriers for example) to arrive at a junction point simultaneously, and thus to interfere with the operation of the system. To avoid occurrences of this character, such systems have in some instances been equipped with apparatus for delaying the advance of articles on one conveyor until the intersection or junction is clear.

However, apparatus as heretofore provided for these purposes has not proven entirely satisfactory for various reasons. It has been customary to effect this intercontrol by transmitting the motion of a feeler, which cooperates with objects on one conveyor, and coacts through a mechanical leverage with mechanism which moves or holds an obstruction in the path of articles approaching the junction on the other conveyor. It not infrequently happens that due to spatial or structural requirements, the usually relatively large number of operating parts of such intercontrol systems must be increased, or some of these parts disposed in inaccessible positions, or again be made of special sizes or weights, in order to secure the proper action of such apparatus. In still other cases the action of the intercontrol mechanism has been relatively slow or sluggish.

Objects of the present invention are to provide improved apparatus of this character which is free from the aforementioned objectionable features; to provide apparatus for these purposes which is readily adaptable to various positions without material alteration; to provide apparatus of this class which is sensitive, quick and positive in action; to provide non-interference apparatus of strong durable construction, consisting of few parts, which are relatively simple and inexpensive to manufacture; and also to provide apparatus of the class described having an improved construction and arrangement of parts.

In the drawing,

Fig. 1 is a top plan view of a conveyor system equipped with one embodiment of this invention;

Fig. 2 is a section taken substantially along the line 2—2 of Fig. 1, with certain parts omitted for the purposes of illustration;

Fig. 3 is a side elevation of an operating lever and yoke shown in Fig. 1; and

Figs. 4 and 5 are respectively side and end elevations of the yoke shown in Figs. 1 and 3.

The features of the invention are illustrated in the drawings as embodied in a system comprising belt conveyors 10, 11 having intersecting paths of movement, the main conveyor 10 passing above the branch conveyor 11. The main conveyor is provided with side frames 12. Likewise the branch conveyor is equipped with the side frames 13, which may be of the usual construction. A deflector 14 is mounted to pivot upon a post 16 carried by a bracket 17 attached to the side frame of the branch conveyor. A deflector 14 is also of sufficient length to extend obliquely across the intersection of the two conveyors so that the free end of the deflector may rest against any suitable fixed abutment, the latter being provided in this embodiment by the side frame 12 of the main conveyor. This deflector is freely movable from the position shown in Fig. 1, to a position at one side of the main conveyor belt 10. All articles approaching the intersection on the belt 11 are thus deflected onto the belt 10 while articles approaching on the belt 11 pass through the intersection without interference.

In order to avoid interference between articles arriving at the intersection of the main and branch conveyors, apparatus is provided for delaying the advance of articles on the branch conveyor until such time as articles approaching or about to enter the intersection from the main conveyor have advanced sufficiently to clear the intersection. In this way articles travelling on the main conveyor are given the right of way over those arriving on the branch conveyor. The apparatus for delaying the advance of articles on the branch conveyor comprises a vertically disposed rotary shaft 18 mounted in upper and lower radial bearings 19 and 21, and equipped with a thrust collar 22, which may ride on the lower bearing 21 and thus support the shaft in proper position. The radial bearings are mounted upon any fixed portion of the apparatus, as on the structural members 23 and 24. An operating arm 26 is rotatably mounted on upper portion of the rotary shaft 18 and is provided with a spring seat 27. Another arm 28 is fast on the lower portion of the rotary shaft and provided at its outer end with an offset portion or tongue 29. This tongue is arranged to extend through a registering opening in the side frame into the path of articles, such as trays, boxes and the like, which are approaching the intersection on the branch conveyor.

A substantially U-shaped yoke member 31 is fixedly mounted upon the shaft 18 with the arms

of the yoke embracing the end of the operating arm 26. The lower end of this yoke is provided with a spring seat 32, and a coil spring 33 is disposed on the seats 27 and 32, thereby providing a resilient means for transmitting force from the operating arm 26 to the yoke 31. The end of the operating arm 26 is provided with a boss 34 which carries an adjusting screw 36. This screw is arranged to engage an abutment 37 provided by the yoke. The screw and the yoke thereby constitute the opposed abutments which are engageable upon movement of the arm 26 in a counterclockwise direction to turn the yoke, and therefore the shaft 18 and the lower arm 23 carried thereby, in counterclockwise direction. The arm 26 is normally urged in this direction by resilient means, such as the tension spring 38, which is attached to the arm 26, and to an eye 39 carried by an upright member 41 of the frame. A deflector guide 42 may also be arranged to direct articles toward the arresting mechanism and along the side of the conveyor on which this mechanism is disposed.

In order that the arm 28 may be advanced into the path of an article and thereby delay the progress of the same, while an article is approaching the intersection on main conveyor 12, a feeler or rod member 43 is disposed longitudinally above this conveyor in the path of articles arriving thereon. Preferably the ends of this rod are turned upwardly to avoid damage to the material being carried. As shown more clearly in Fig. 2, the structure for suspending this rod comprises hangers 44 and 46 carried by overhead supports 47, and providing mountings for transversely extending rotatable shafts 48 and 49. Bent arms 51 and 52 are fixed to these shafts as by being pinned or riveted thereto, as indicated at 53. The lower or depending ends of these arms are provided with eyes which receive hinge pins 54 mounted in pads or attaching plates 56 secured to the rod 43, thereby providing a pivotal connection between each of the arms 51 and 52 and the feeler member 43. To assure a smooth, easy and yet sensitive movement of this feeler member, the upper end of one of the arms, as the arm 51, is provided with a counterweight 57. The upper end of the other arm 52 is equipped with a laterally offset bracket 58, to which is attached a tilttable fluid switch 59 provided with contacts 61 and 62. The rotary shaft 49 carries, preferably at a point outside one of its hangers 46, a radially disposed pin 74, which is adapted upon sufficient rotary movement of this shaft to engage a fixed abutment or pin 75 attached to the hanger or other fixed support and thus to limit rotary movement of this shaft. Electrical energy is conducted from the mains 63 and 64 through a wire 66 to the contact 61, and through another wire 67 to a solenoid 68 and then to the wire 69, which is attached to the contact 62. A manually operable switch 71 may also be interposed in the line 63, 64. The movable core 72 of the solenoid 68 is pivotally connected by means of a plunger rod 73 to the operating arm 26.

In the operation of the apparatus, assuming that an article such as the box 76, indicated in dot and dash lines, on the main conveyor is about to enter the intersection at the same time that a similarly indicated box 77 reaches the same relative position on the branch conveyor, the feeler rod 43, due to engagement with the box 76, will be moved forwardly, as shown in

Fig. 2, and such movement will serve to tilt the switch 59 to complete the circuit from the line 63, 64 through this switch and the solenoid 68, thereby energizing the latter and drawing the arm 26 in a clockwise direction. This movement of the arm 26 is transmitted through the coil spring 33 to the yoke 31, the rotary shaft 18 to the arm 23, thereby moving the latter into the path of the box 77 and effectively preventing further forward movement of this box. The arrangement of spring 33 assures that articles, as the box 77, will not be damaged by having the tongue 29 of arm 28 forced into or against the side of the same as would otherwise be the case if the forward end of such article had passed the tongue before the feeler 43 were actuated. As the box 76 passes into the intersection its forward end engages the deflector 14 and moves the latter to one side. As the rear end of the box 76 passes from under the upwardly curved end of the feeler rod 43, the latter will recede smoothly to its normal position, and in so doing will tilt the switch 59 to break the circuit therethrough, and in this way deenergize the solenoid 68. When the feeler rod returns to its normal position in the path of approaching articles the pin 74 rests against the abutment or pin 75 and thus prevents overswinging of the rod and assures that the switch 59 will remain open. The tension spring 38 then becomes effective to move the operating arm 26 in a counterclockwise direction to its normal or inoperative position. This movement is transmitted through the adjusting screw 36 abutment 37 and yoke 31 to the rotary shaft 18, and thus causes the latter to retract the arm 28 from the path of the box 77, thereby permitting the latter to advance with the conveyor. As this box advances it engages the deflector and moves the latter to the position shown in Fig. 115 1, where the free end of the deflector rests firmly against the side frame 12 of the main conveyor 10, and thus the deflector provides a firm guide for directing the box 77 on to the main conveyor. It should also be noted that the guide 42 of the branch conveyor is arranged to cooperate with a diagonal guide 81 and a supporting plate 82 for assisting in guiding articles, such as the box 77, on to the conveyor 10.

With apparatus such as that described, it will be observed that it is possible to avoid the use of direct mechanical connections between a feeler such as the member 43, and article-delaying mechanism, such as the arms 26 and 28 for example. This overcomes quite a serious difficulty as it is often desirable to arrange one of the conveyors, as the conveyor 10 for example, immediately adjacent a column or other support which can not conveniently be modified to provide sufficient space for the operating mechanism, or if so modified the apparatus usually requires special parts of unusual construction which often must be placed in inaccessible positions. While the solenoid 68 has been shown as mounted upon the upper frame member 97, it will be clear that this solenoid is readily adaptable for mounting in various convenient positions. It will also be evident that it is within the scope of this invention to reverse the arrangement of the spring 38 and the solenoid 68, so that the spring tends normally to move the operating arm 26 in a clockwise direction, while the solenoid may be effective for moving the arm in a counterclockwise direction. Moreover, the features of this novel arrangement do not depend entirely upon the use of the sole- 150

noid, as it is contemplated that an electric or other type of motor or prime mover of which a solenoid is to be considered representative, might be made to serve approximately the same purpose as the solenoid. Many of the advantages of the present invention may be gained by substituting any of the various types of prime movers for the solenoid 68.

It should be understood that the present disclosure is for the purpose of illustration only and that this invention includes all modifications and equivalents which fall within the scope of the appended claims.

We claim:

15 1. Apparatus of the class described comprising conveyors having intersecting paths, a rotary shaft disposed at one side of one conveyor, an arm fast on this shaft and movable from a position at one side of this conveyor to a position in the path of articles carried thereby, an operating arm rotatable on this shaft, an arm rigid with the shaft, resilient means between the operating and rigid arms for transmitting force from the operating arm to the shaft for moving the first-named arm into the path of articles, and opposed abutments on the operating and rigid arms, these abutments being engageable for retracting the first-named arm from the path of the articles on the conveyor.

30 2. Apparatus of the class described comprising conveyors having intersecting paths, a rotary shaft disposed at one side of one conveyor, an arm fast on this shaft and movable from a position at one side of this conveyor to a position in the path of articles carried thereby, an operating arm rotatable on this shaft, an arm rigid with the shaft, resilient means between the operating and rigid arms for transmitting force from the operating arm to the shaft for moving the first-named arm into the path of articles, opposed abutments on the operating and rigid arms, these abutments being engageable for retracting the first-named arm from the path of the articles, and means providing for adjustment of the relative position of at least one of the abutments.

35 3. Apparatus of the class described comprising conveyors having intersecting paths, a rotary shaft disposed at one side of one conveyor, an arm fast on this shaft and movable from a position at one side of this conveyor to a position in the path of articles carried thereby, an operating arm rotatable on this shaft, an arm rigid with the shaft, resilient means between the operating and rigid arms for transmitting force from the operating arm to the shaft for moving the first-named arm into the path of articles, opposed abutments on the operating and rigid arms, these abutments being engageable for retracting the first-named arm, means tending to move the operating arm in one direction, a prime mover for moving the operating arm in the opposite direction, and means for controlling the prime mover in response to movement of articles on the other conveyor.

40 4. Apparatus of the class described comprising conveyors having intersecting paths, a rotary shaft disposed at one side of one conveyor, an arm fast on this shaft and movable from a position at one side of this conveyor to a position in the path of articles carried thereby, an operating arm rotatable on this shaft, an arm rigid with the shaft, resilient means between the operating and rigid arms for transmitting force from the operating arm to the shaft for moving the first-named arm into the path of articles, op-

posed abutments on the operating and rigid arms, these abutments being engageable for retracting the first-named arm, and a guide for directing articles along the side of the conveyor on which these arms are mounted.

45 5. Apparatus of the class described comprising conveyors having intersecting paths, means movable into and out of the path of articles on one conveyor, means tending to move the movable means to one of these positions, electromagnetic means for moving the movable means to the other of these positions, a tilttable fluid switch for controlling the electromagnetic means, and other movable means depending into the path of articles on the other conveyor and operable on engagement with such articles for tilting the switch.

50 6. Apparatus of the class described comprising conveyors having intersecting paths, means movable into and out of the path of articles on one conveyor, means tending to move the movable means to one of these positions, electromagnetic means for moving the movable means to the other of these positions, a tilttable fluid switch for controlling the electromagnetic means, other movable means extending into the path of articles on the other conveyor and operable on engagement therewith for tilting the switch, and means for limiting tilting movement of the switch to prevent excessive movement thereof.

55 7. Apparatus of the class described comprising conveyors having intersecting paths, means movable into and out of the path of articles on one conveyor, means tending to move the movable means to one of these positions, electromagnetic means for moving the movable means to the other of these positions, a tilttable fluid switch for controlling the electromagnetic means, rotatable shafts disposed transversely above the other conveyor, arms depending from these shafts, the tilttable switch being movable with one of these arms, a member pivotally connected to the lower ends of these arms and disposed longitudinally in the path of articles on the latter conveyor, whereby movement of said member due to engagement with an article is effective to actuate the switch.

60 8. Apparatus of the class described comprising conveyors having intersecting paths, means movable into and out of the path of articles on one conveyor, means tending to move the movable means to one of these positions, electromagnetic means for moving the movable means to the other of these positions, a tilttable fluid switch for controlling the electromagnetic means, rotatable shafts disposed transversely above the other conveyor, arms extending across these shafts and affixed thereto, these arms having their lower ends depending above the conveyor and substantially in alignment longitudinally thereof, the tilttable switch being movable with one of these arms, a member pivotally connected to the lower ends of these arms and disposed longitudinally in the path of articles on the latter conveyor, and a counterweight on the upper end of at least one of the arms.

65 9. Apparatus of the class described comprising conveyors having intersecting paths, means movable into and out of the path of articles on one conveyor, means tending to move the movable means to one of these positions, electromagnetic means for moving the movable means to the other of these positions, a tilttable fluid switch for controlling the electromagnetic means, rotatable shafts disposed transversely above the other con-

veyor, arms extending across these shafts and affixed thereto, these arms having their lower ends depending above the conveyor and substantially in alignment longitudinally thereof, the tiltable switch being mounted on the upper end of one of these arms, a counterweight on the upper end of the other of these arms, and a member pivotally connected to the lower ends of these arms and disposed longitudinally in the path of articles 10 on the latter conveyor, whereby movement of said member due to engagement with an article may be effective to actuate the switch.

10. Apparatus of the class described comprising conveyors having intersecting paths, means movable into and out of the path of articles on one conveyor, means tending to move the movable means to one of these positions, electromagnetic means for moving the movable means to the other of these positions, a tilttable fluid switch for controlling the electromagnetic means, rotatable shafts disposed transversely above the other conveyor, arms extending across these shafts and affixed thereto, these arms having their lower ends depending above the conveyor and substantially in alignment longitudinally thereof, the tilttable switch being mounted on the upper end of one of these arms, an abutment fast on the shaft on which this arm is mounted, a fixed abutment engageable therewith for limiting rotary 30

movement of the shaft and thereby preventing excessive movement of the switch, a counterweight on the upper end of the other arm, and a member pivotally connected to the lower ends of these arms and disposed longitudinally in the path of articles on the latter conveyor whereby movement of said member due to engagement with an article, may be effective to actuate the switch.

11. Apparatus for avoiding interferences of conveyed articles at the intersection of two conveyors, comprising a movable arm which in one position permits and in another position prevents movement of the articles on one conveyor, a shaft to which said arm is secured normally holding the arm in the movement-permitting position, means for rotating said shaft to move the arm into its movement-preventing position including a rod normally in the path of travel of articles on the other conveyor and hangers for said rod, electromagnetic means connected to said shaft rotating means, and a switch carried by one of said rods, which switch when the rod is contacted by an article on the other conveyor closes a circuit by which the electromagnetic means is energized causing the rotation of the 100 shaft and movement of the arm into its movement-preventing position.
